DRAFT APPLIANCE FOR MINE AND OTHER CARS

Audley Hart Stow, Charleston, W. Va.; Edith S. White, executrix of the estate of Audley Hart Stow, deceased, assignor to Sanford Investment Company, Wilmington, Del., a corporation of Delaware

Original application November 15, 1920, Serial No. 424,132. Divided and this application October 21, 1926, Serial No. 143,187

11 Claims. (Cl. 105—364)

This invention relates to certain improvements in and relating to draft appliances for mine cars and the like; and the objects and nature of the invention will be readily understood by those skilled in the art in the light of the following explanation of the accompanying drawings illustrating what I now believe to be the preferred mechanical expressions or embodiments of my invention from among other forms, constructions and arrangements within the spirit and scope 10 thereof.

This application is filed as a division of my pending application Serial No. 424,132, for improvements in Mine cars and the like, and for this application, I claim the date of filing of said 15 parent case, namely, Nov. 15, 1920.

This invention relates particularly to mine cars for hauling coal and similar minerals and ores.

The object of this invention is to provide spring draft appliances, more particularly to the end 20 that the length of life of the equipment may thereby be increased.

With this and other objects in view, the invention consists in certain novel features in construction and in combinations and arrangements 25 as more fully and particularly set forth and pointed out hereinafter.

Referring to the accompanying drawings, in which, in all longitudinal views, the left end, as shown, is considered the front end, and the right 30 end, the rear end of the car.

It will be understood that references made herein to "original figures" apply to the figures of my said copending parent application.

Fig. 1 is a bottom plan of a traction truck constructed in accordance with my invention, the 35 axles being broken away, the lading holding body of my complete car not being shown, and is the same as original Fig. 1, except that certain parts have been broken away, so as to show in solid 40 lines, what was shown in original Fig. 1, in dotted lines.

Fig. 2 is a sectional side elevation of the mine 45 car of my invention, the rear end portion of the car being shown in vertical longitudinal section.

Fig. 3 is a detail vertical longitudinal section through one end portion of the car.

Fig. 4 is a detail cross section through a portion 50 of the lading bottom and the spring draw head housing of Fig. 3.

Fig. 5 is a detail top plan of another form of car end structure, partially broken away to expose the longitudinal horizontal section.

Fig. 6 is a detail longitudinal vertical section 55 showing a portion of one end of the car and the structure of Fig. 5.

Fig. 7 is a view similar to Fig. 6, and is the same as original Fig. 28, except that it shows in solid lines what was shown in dotted lines, in original Fig. 28.

Fig. 8 is a view similar to Fig. 7, showing a 60 still different form of draw bar, and is the same as original Fig. 31.

Fig. 9 is a view similar to Fig. 7, showing an automatic car coupling device, and is the same 65 as original Fig. 38, except that the dotted lines have been omitted.

Fig. 10 is a view similar to Fig. 9, and is the same as original Fig. 38, except that it shows in solid lines what was shown in original Fig. 38 in dotted lines.

The transverse "out to out" dimensions of 70 mine cars, more particularly, are limited by the conditions, the object of this invention being in part to attain the maximum transverse lading dimensions reasonably attainable.

With the old type mine cars, the longitudinal 75 wooden planks which had heretofore formed the lading bottom, were placed above the car axles, and thus necessarily, quite high off the mine car track. With my new type mine car, I employ preferably a strongly designed traction truck, 80 which thus enables me to get my lading bottom not merely below the car wheel axles, but also as close to the mine car track as is otherwise practical, in order to attain maximum lading 85 depth. My lading bottom will therefore be also herein termed a sub-axle lading bottom, which term is to be understood to apply to any lading bottom or any portion of the lading bottom below the plane passing through the tops of the car 90 wheel axles.

I preferably employ longitudinal supporting 95 side beams, the axle journal bearings being secured to the side beams above the bottom portions of the side beams. I am thus enabled to support the lading bottom by the bottom portions of the side beams, so that my improved sub-axle lading bottom is below the plane passing through the tops of the car wheel axles. The side beams may also support the lading body. Suitable end reinforcements may also be provided which will obviate the necessity for a center thrust beam extending throughout the length of the car. Suitable spring draft appliances may also be provided, which will increase the length of life, of the equipment.

The several parts of my improved traction truck 100 may be riveted or otherwise suitably attached together.

As shown in Fig. 2, the car wheels 1, resting on the track 2, support the car wheel rotary axles 3. 110

The car axles are passed through integral cast axle boxings 4, riveted to the flanged metal side beams 5. The sheet metal lading siding 6, is supported, mainly, by the flat strap belts 7, 7A.

5 The end beams 8, 8A, Fig. 1 are secured, at their ends, to the ends of the side beams 5. The primary lading bottoms 9, 9A, 9B, are shown as three spaced apart approximately rectangular sheet metal plates riveted to the under side of the bottom flanges 5A, of the side beams 5. The secondary lading retaining bottoms 10, 10A, 10B, also sheet metal plates and spaced apart, are so secured to the adjoining lading primary lading bottoms, and to the end beams 8, 8A, as shown, 15 that they form a complete lading bottom from end to end of my improved traction truck.

Figs. 1 and 2 illustrate an end dump car of my improved design, the front end being provided with a lift gate, to permit the suitable discharge 20 of the lading, when the car is tilted forward in the end dumping position.

As shown in Fig. 6, the secondary lading retaining bottom 10, is passed up over the upper flange 8B, of the front end channel 8, so as to suitably 25 guide the lading over said end channel when the car is tilted forward in the end dumping position. There is thus obviously left below the said secondary lading bottom, room for the draft appliances, see also Fig. 7.

30 As shown in Fig. 3, the rear main lading bottom 9B, extends the full length of the portion of the traction truck shown, passing under the bottom flange 8C, of the rear end channel 8A, for the full 35 width of said flange, although I do not wish to limit myself to the precise details shown. The rear end of the traction truck may evidently be the same, whether for an end dump car, or for a sidewise dumping car.

The spring draft appliance as shown in Fig. 3, 40 is adapted to either or both ends of the car, and consists, more particularly, of the drawhead composed of the double draw bars 11, 11A, and the draw bar housing 12, 12A. The upper draw bar or draw head 11, partly broken away, and the 45 lower draw bar or draw head 11A, are welded together at their forward ends so as to form a round spindle 11B, adapted to receive the double coil springs 13, 13A. The draw head spring spindle and springs operate between the draw head housing side plates 12, 12B, see also Fig. 4.

50 As shown in Fig. 4, the housing side plates 12, 12B, are provided with ample integral horizontal bottom flanges 12C, bearing on the main lading bottom 9B. These bottom flanges may be riveted 55 or otherwise suitably attached to the said lading bottom. The side plates are to be cut so as to avoid unnecessary loss of lading space. The housing cover plate 12A, has side flanges 12D, the said 60 flanges making reasonably close contact with the outer faces of the side plates, so as to make a reasonably tight housing covering, as shown, and may be held in working position, as by nuts and bolts.

65 The coil springs 13, 13A, Fig. 3, operate between the rear pivot bridle 14, and the thrust plate 15. The pivot bridle has a central flat portion 14A, apertured to receive the draw bar spindle 11B, with flanges 14B, on either side by means of 70 which the pivot bridle is riveted in working position to the housing side plates.

The forward bridle plate 16, still Fig. 3, also has a flat central portion 16A, between two flanges 16B, by means of which the forward bridle plate 75 is also riveted between the housing side plates.

The central portion is apertured to receive, quite loosely, the hollow shank 15A, of the thrust plate 15.

The thrust plate 15, still Fig. 3, may obviously be approximately cylindrical so as to form a suitable bearing plate for the coil springs 13, 13A, and is apertured in the center so as to neatly receive the draw bar spindle 11B. 80

The shock plate 17, still Fig. 3, is also apertured to receive neatly the draw bar spindle 11B, and is held in place by the spindle key 11b. When the tractive haulage strain is sufficient in amount to bring the shock plate to a bearing against the central portion 16A, of the forward bridle plate, the said forward bridle plate will thereafter take 90 care of the tractive haulage strains, until these strains are again reduced below the resistance of the coil springs. 85

The draw head spindle 11B, still Fig. 3, is shown as being on a relatively flat slope or pitch, so that 95 obviously the binding of the parts, due to the fact that the spindle is not quite in line with the tractive haulage strains, will not be seriously objectionable.

As shown in Figs. 1 and 2, the bumper plate 18, 100 in vertical cross section, is of channel form, its upper and lower flanges 18A, 18B, respectively, sliding longitudinally of the car, within the upper and lower flanges 8D, 8C, respectively, of the rear end channel 8A. The wood springs 19, see also Fig. 1, serve to cushion the haulage impacts. Obviously, the bumper plate 18, Fig. 1, may be termed a center bumper. 105

The side bumpers 18C, Figs. 5 and 6, also consist, obviously, of formed up sheet metal, and in 110 vertical cross section, are also of channel form. Again also, the side bumpers slide within the end channel 8A, the cushioning material in this case being solid wood beams 19A. These side bumpers are spaced apart, so as to provide ample clearance, obviously, for coupling purposes. The draw head 11C, is riveted direct to the web plate 8E, of the front end channel 8, by the rivet 19. 115

The draw head 11C, Figs. 5 and 6, is shown as a double draw head, consisting of the upper 120 draw head or draw bar 11D, and the lower draw head or bar 11E, formed up out of flat strap iron, of approximately, horizontal U-shape.

The draw head 11C, as shown in Figs. 5 and 6, 125 may obviously however be provided with an approximately horizontal spring draw head spindle 11F, see Fig. 7, similar, obviously, to the spring draw head spindle, 11B, Fig. 3. It will be evident this draw head is in line with the supporting side beams 5. The draw head spindle 11F, 130 is shown as passing through the web plate 8E, of the end channel 8, about midway between the upper and lower flanges 8B, 8F, respectively.

The draw head 11G, Fig. 8, may also be described as a center draw bar, or center draw head, 135 for the obvious reason that it is located approximately midway between the upper and lower flanges 8B, 8F, respectively, of the front end channel 8. This draw head is shown as a single draw head, and used with the clevis coupling 20. 140 The draw head shank 11H, may evidently also be a suitable coil spring spindle, also placed in the vertical center of the end channel, and thus, obviously, quite close to the lading bottom.

My improved traction truck particularly read- 145 ily admits of automatic couplings, similar to the automatic coupling 11I, Fig. 9, which may have a broad base 11J, by means of which it may be riveted to the forward face of the web plate 8E, of the end channel 8, by the rivets 20. The said 150

automatic coupling may of course also have the approximately horizontal spring shank 11K, extending rearwardly through the said end channel, and equipped with the coil spring action as herein outlined, or with other spring action, suitable for the purpose.

The automatic coupling 11I, Figs. 9 and 10, is, obviously, a cast coupling or draw head, as distinguished from the wrought draw heads previously described. I however do not wish to be restricted to the precise details shown, but hold myself at liberty to make changes and alterations as are within the spirit and scope of my invention.

15 The lading bottom may be reinforced, at the end, by a sheet metal plate 9c, Figs. 1 and 2, riveted to the main lading bottom, by the rivets 21, thus giving a substantial anchorage to the rigid draw head 11L, 11M.

20 As shown in Fig. 2, the lading body end lift gate 22, is provided with the usual lift gate hook 22A.

What I claim is:—

1. In a mine car, the combination of axles, 25 side and connecting end sills, a lading bottom the lower portions of which lie in a plane below the horizontal plane of the tops of the axle journals and also below the horizontal plane of the upper portions of the side sills, a draw-head 30 housing arranged above said lading bottom adjacent one end sill, a spring in said housing, and a draw-head extending into the housing in relation with said spring and over the adjacent end sill.

35 2. In a mine car, the combination of axles, side connecting end sills, a stationary lading bottom the lower portions of which lie in a plane below the horizontal plane of the tops of the axle journals and also below the horizontal plane of the upper portions of the side sills, a draw-head 40 housing arranged above said lading bottom adjacent one end sill, a spring in said housing, and a draw-head extending into the housing and over the adjacent end sill.

45 3. In a mine car, in combination, a supporting frame having a transverse end structure and a lading bottom the lower portions of which lie in a plane below the horizontal plane of the journals of the car axles and also below the upper portions of the side members of the supporting 50 frame, a haulage draw bar means including a spring-cushioned longitudinally-movable draw bar located above said bottom and extending over said end structure, and guiding means for said movable draw bar.

55 4. In a mine car, in combination, a supporting frame having a transverse end structure and a stationary lading bottom the lower portions of which lie in a plane below the horizontal plane of the journals of the car axles and also below the upper portions of the side members of the supporting frame, a haulage draw bar means including a spring-cushioned longitudinally-movable draw bar located above said bottom and extending over said end structure, and guiding means for said movable draw bar.

60 5. In a mine car, the combination of axles, side sills, end sill structures connected with the side sills and having a transverse metal member with an upright back face, a lading bottom the lower portions of which lie in a plane below the horizontal plane of the tops of the axle journals and also below the horizontal plane of the upper 65 portions of the side sills, a spring draw-head 70 housing arranged above said lading bottom

adjacent one end sill, and a draw-head extending into the said housing and also extending away from the said housing and over the upright plane of the back of the said end structure metal transverse member.

6. In a mine car, in combination, a supporting frame having a transverse end structure including a transverse metal member with a substantially upright back wall, a lading bottom the lower portions of which lie in a plane below the horizontal plane of the tops of the journals of the car axles and also below the horizontal plane of the upper portions of the side members of the supporting frame, a haulage draw bar means including a spring-cushioned longitudinally-movable draw bar extending in part substantially horizontally in an upright plane that cuts said upright wall of said transverse member of said end structure, and guiding means for said movable draw bar.

7. In an end dump mine car, the combination of axles, side and connecting end sills, a lading bottom having a portion lying below the horizontal plane of the tops of the axle journals and also below the horizontal plane of the upper portion of the end sill, said end sill having an upright wall, a lading deflector rising from said lower portion of the bottom substantially to said plane for guiding the lading over the end sill during dumping, a spring located beneath said deflector and inside said upright wall, and a draw head engaged with said spring and extending longitudinally past the upright wall of said end sill.

8. In an end dump mine car, the combination of axles, side and connecting end sills, a lading bottom having a portion lying below the horizontal plane of the tops of the axle journals and also below the horizontal plane of the upper portion of the end sill, said end sill having an upright wall, a lading deflector rising from said lower portion of the bottom substantially to said plane for guiding the lading over the end sill during dumping, a spring located beneath said deflector and inside said upright wall, and a draw head engaged with said spring and extending through the upright wall of said end sill.

9. In an end dump mine car, the combination of axles, side and connecting end sills, a lading bottom having a portion lying below the horizontal plane of the tops of the axle journals and also below the horizontal plane of the upper portion of the end sill, said end sill having an upright wall, a lading deflector rising from said lower portion of the bottom substantially to said plane for guiding the lading over the end sill during dumping, a coil spring located beneath said deflector with its axis substantially parallel to said deflector, and a draw head engaged with said spring and extending through said deflector and longitudinally past the upright wall of said end sill.

10. In an end dump mine car, the combination of axles, side and connecting end sills, a lading bottom having a portion lying below the horizontal plane of the tops of the axle journals and also below the horizontal plane of the upper portion of the end sill, said end sill having an upright wall, a lading deflector rising from said lower portion of the bottom substantially to said plane for guiding the lading over the end sill during dumping, a coil spring located beneath said deflector with its axis substantially horizontal and parallel to the length of the car, said spring being engaged with said upright wall, and a draw

head engaged with said spring and extending through the upright wall of said end sill.

11. In an end dump mine car, the combination of axles, flanged side and connecting end sills, 5 a lading bottom including a portion lying below the horizontal plane of the tops of the axle journals and secured to the bottom flanges of the end and side sills, a lading deflector rising from said bottom portion to the upper portion

of the end sill for guiding lading over said end sill during dumping, said bottom portion, upright wall and deflector constituting a substantially closed draw head housing, a spring located in said housing, and a draw head engaged with said spring and extending longitudinally past the upright wall of said end sill.
